TRAVELING WAVE ELECTRON DISCHARGE DEVICES

Richard H. Geiger, Emerson, N. J., assignor to International Telephone and Telegraph Corporation, Nutley, N. J., a corporation of Maryland

Application October 29, 1954, Serial No. 465,513

18 Claims. (Cl. 315—3.5)

This invention relates to traveling wave electron discharge devices and more particularly to gas discharge devices for introducing a circuit loss along the path of a traveling wave in such electron discharge devices to prevent both undesirable oscillations and propagating modes therein.

In the traveling wave type of tube for amplification in wideband microwave systems, the useful range of amplification which can be utilized is limited by a tendency to generate self-sustained oscillations as the amplification is increased. This effect is usually due to mismatch between the output circuit of the device and the load circuit over all or part of the wide range of frequencies to be amplified. Due to such mismatch, energy of at least certain frequencies is reflected back toward the input end of the amplifying device. When the reflected wave is not attenuated in its travel in a direction opposite to the motion of the electron stream, some energy reaching the input end of the device is reflected from the input end causing the generation of self-sustained oscillations. Thus, the energy reflected or transmitted back to the input end must be attenuated if the tube is to remain stable.

In most traveling wave devices heretofore proposed, particularly the helical transmission line type, attempts have been made to overcome this tendency of generating self-sustained oscillations by employing resistive or lossy material to attenuate the reflected waves. The distribution of the resistive material along the entire length of the helix, along a major portion thereof, in lump form, or as a part of the helical conductor itself limited the gain and power output of the device. Where the resistive material is spaced from the conductor, such as in the lumped form, it is less effective and requires a larger amount in order to absorb the reflected energy. Further, the utilization of an organic loss material, such as carbon, or aquadag, makes the out-gassing of the traveling wave device more difficult since the organic material entraps more gases than would normally be found when the organic material is omitted.

It is an object of the present invention, therefore, to provide an improved means for introducing a circuit loss in the path of the radio frequency wave of a traveling wave device so as to prevent self-sustaining oscillations and yet obtain high gain and maximum output power.

It has been discovered that in one approach to obtain high gain and maximum power output that the attenuating means must be concentrated within the smallest axial length of the helix possible and with proper impedance match. The conductivity of the helical conductor must be maintained high, the input section of the helix must be as lossless as possible and sufficiently long to enable the gaining wave of the energy launched on the propagating structure to achieve a sufficient amplitude and the output section of the helix must also be lossless and as long as permissible for achievement of the desired gain and power output. It is, therefore, another object of

5 this invention to provide the wave propagating structure of a traveling wave device with an attenuator having the relationship and so disposed relative to the propagating structure to satisfy the above-mentioned requirements which have been found desirable for high gain and maximum power output.

10 One of the features of this invention is the utilization of a gaseous discharge device having an electron density upon ionization such that the collision frequency of the electrons therein is approximately equal to the angular frequency of the propagating microwave energy to intercept part of the high frequency field of the propagated energy with a minimum of reflection or radiation of the radio frequency energy and which will absorb the microwave energy in a minimum axial distance along the propagating structure.

15 Another feature of this invention is the provision of a gas discharge device having an envelope of annular-like cross-section, the ends of which are tapered radially relative to the propagating structure, disposed concentrically about the propagating structure and within the field of the microwave energy transmitted on the propagating structure.

20 Other features of this invention include the shaping 25 of the envelope of the gas discharge device to position the ionized gas within a stronger field region of the electromagnetic field present about a helical propagating structure whereby the ionization of the gas within the various shaped gaseous discharge devices may be accomplished by potential difference, pulsed potential sources 30 associated with cold cathode material, and the radio frequency field of the propagated wave alone or in combination with the intensity of the longitudinal magnetic field present in a traveling wave device for achievement 35 of gyroresonance.

The above-mentioned and other features and objects of this invention will become more apparent by reference to the following description taken in conjunction with the accompanying drawings, in which:

40 Fig. 1 is a diagrammatic representation of a traveling wave electron discharge device incorporating a gas discharge attenuator in accordance with this invention;

45 Fig. 2 is an enlarged longitudinal cross section of the gas discharge device of Fig. 1;

Fig. 3 is a cross-sectional view taken along line 3—3 of Fig. 2;

Fig. 4 is a longitudinal cross-sectional view of another embodiment of this invention;

Fig. 5 is a cross-sectional view taken along line 5—5 of Fig. 4;

50 Figs. 6, 7, 8 and 9 are longitudinal cross-sectional views, partially diagrammatic, of still other embodiments of this invention; and

Fig. 10 is a diagrammatic illustration of a traveling wave electron discharge device incorporating still another embodiment of this invention.

55 Referring to Fig. 1, there is shown an illustrative embodiment of a discharge device adapted to be used as an amplifier at microwave frequencies. The arrangement shown comprises an electron beam tube including an 60 evacuated envelope 1. The envelope 1 may be composed of a low-loss insulated material, such as glass or quartz, or a suitable metal having non-magnetic properties. The envelope 1 is provided at one end with a known type of electron gun 2 for producing an electron beam or stream of either the pencil type or hollow type. The electron beam emerging from gun 2 in the illustrated embodiment is of the pencil type and travels along a path substantially axially of envelope 1 and passing through input coupler 3. The electron stream is further concentrated 65 and guided parallel to the axis of envelope 1 within the space surrounded by helical transmission line 4 by a lon-

itudinal magnetic field produced by a permanent magnet or an electromagnet as represented by 5. Electrode 6 serves to collect the electrons arriving at the end of envelope 1 after passage through the helical propagating structure 4. While the propagating structure of the traveling wave tube is herein shown and described as being a helical transmission line, the propagating structure need not necessarily be limited to such a helical structure, but may include transmission lines composed of baffles and similar devices.

The helix 4 is wound to have a length of a plurality of wavelengths at the frequency to be amplified along its axis. The helix is supported to provide a rectilinear structure coaxial of the axis of envelope 1 by a non-conductive structure shown in this instance to comprise a series of non-conductive rods 7 equally spaced around the circumference thereof. A non-conductive tubing co-extensive with the length of the helix may be substituted for the rods. The rods or tubing may be composed of a suitable ceramic material disposed between the helix 4 and the envelope 1 and positioned axially of envelope 1 by discs 8 and 9 disposed at the extremities of the helix and in a transverse relation with respect to envelope 1. The helix 4 is joined to the input coupler 3 by an input impedance matching section 10 and the output coupler 11 by the output impedance matching section 12. These matching sections are simply extensions of the helix in which the spacing between adjacent turns is increased along the circumference of the helix and act as tapered transmission lines to provide a wave transmission path of uniformly changing impedance from the relatively low impedance at the end of the couplers 3 and 11 to the relatively high impedance of the center portion of helix 4 with a minimum reflection of energy back to the signal source.

In order to utilize the device in an operable system, there is provided an input wave path represented by the dotted input waveguide 13 into which there is introduced the input wave signal to be amplified. An output wave path shown as the output waveguide 14 serves to transfer the amplified output wave to a load circuit. The wave from the input waveguide 13 and coupler 3 travels along the circumference of the helix 4 at a speed approximating that of light, but at a linear velocity along the axis of the tube which approximates or is slightly slower than the velocity of the electrons of the beam. As the beam and the radio frequency wave travels along the helix, an interaction takes place whereby energy is transferred from the beam to the wave thereby greatly amplifying the wave. It has been fairly well established in the prior art that the wave launched upon the propagating structure consists of three components, an increasing component, a decreasing component and an unattenuated component. It is, of course, realized that the resulting amplification is accomplished by the interaction between the increasing component of the wave and the electron beam. As the amplified wave reaches the output end of helix 4, it is transferred to the output waveguide 14 by means of output coupler 11. As the amplified wave reaches the impedance matching section 12 at the output end of helix 4, even with an extremely favorable termination, at a given band of frequencies, there will still exist reflected waves at frequencies inside and outside the given band at the output end of the helix. This reflected wave, while it does not enter into the interaction with the electron stream, is propagated back along helix 4 toward the input end with attenuation. The reflected wave will reach the input end of the helix 4 with attenuation equal to the circuit attenuation and will in turn be reflected back toward the output end of the helix. It is obvious that there will be some reflected energy which will result in self-sustaining oscillations, provided there is not enough circuit attenuation to dampen the reflected energy. The circuit

attenuation in the past has been deliberately increased by the addition of an artificial loss along the helix so as to provide a dissipation of the reflected wave which served to increase the range of useful amplification. 5 The introduction of a lossy material in the form of aquadag, however, reduced the gain and power output of the traveling wave device.

In accordance with the principles of this invention, an artificial loss is introduced along a portion of the 10 helix 4 which will increase the range of useful amplification, but which will not reduce the gain and power output of the traveling wave device. The artificial loss of this invention introduced in juxtaposition to helix 4 is provided by gas discharge device 15.

15 Referring to Figs. 2 and 3, a cross-sectional view of one embodiment of my gas discharge device 15 is illustrated as comprising an annular envelope 16 disposed to be in contact with the support rods or tubing 17 of the helical propagating structure 4. The inner surface 20 of envelope 16 is brought as close as possible to the electromagnetic field present about the helix. The envelope 16 is filled with a suitable noble gas, such as helium, neon, argon, krypton and xenon, and is in some manner caused to ionize to function as an attenuator for 25 the propagating structure of a traveling wave electron discharge device.

As is known, a gaseous discharge plasma may act as a propagating medium for microwave and if the electron density of the discharge plasma is adjusted so that 30 the collision frequency of the electrons of the gas is approximately equal to the angular frequency of the propagating microwave energy, the plasma absorbs the microwave energy. The degree of absorption is determined by the magnitude and distribution of the electron 35 density in the radio frequency fields. Therefore, it has been discovered that if a gaseous discharge plasma is located close to the turns of a helical structure, such as helix 4, where the electromagnetic field distribution is at a maximum between the turns of a helix, effective 40 absorption or attenuation will occur.

45 Discharge device 15 is provided with anodes 18 and 19 which in turn are placed across a potential source 20, as illustrated in Fig. 1, which when switch 21 is closed, will establish a potential difference between electrodes 18 and 19 of sufficient value to ionize the gas within envelope 16 to produce a discharge plasma of sufficient electron density whose collision frequency is approximately equal to the angular frequency of the 50 propagated energy such that an absorption or attenuation of the energy will take place. Envelope 16 is provided with ends 22 which are tapered radially with respect to the helix to reduce reflections from the glass envelope 16 and the discharge plasma.

55 The characteristic of the loss medium of this invention is such that most of the electromagnetic energy in the propagating structure is absorbed, and the signal is transmitted through the loss section by the modulation signal energy in the electron stream. At or near the 60 output end of the loss section, the electromagnetic wave is re-excited in the lossless section of the propagating structure by the modulated electron beam. The location of discharge device 15 is a predetermined distance from the input end of structure 4 such that the equation $CN \approx 0.3$ is satisfied, where C is the gain parameter relating the degree of interaction between the electron beam and electromagnetic wave propagated along the 65 propagating structure and N is the number of wavelengths from the input end. Provision of an input portion of helix having a length corresponding to the aforementioned equation insures that the electron stream becomes sufficiently excited according to the radio frequency signal at the input such that an electromagnetic wave is 70 re-excited in the output portion of the helix after encountering the attenuator. This re-excited wave in turn 75

interacts with the modulated beam in a continuous manner as the wave and the beam progress down the tube at practically the same velocity in such a manner that the electromagnetic wave gains in amplitude. The length of the output or lossless section of the helix should satisfy the equation $G = A + BCN - \alpha L$, where G equals the gain of the tube desired, A is a coupling loss figure relating the voltage associated with the increasing wave to the total applied voltage, B is a parameter associated with the increasing wave, C is the gain parameter, N is the length in wavelengths of the propagating structure, α is the fraction of the cold loss which should be subtracted from the gain of the increasing component of the propagated wave and L is the loss in db per wavelength. Providing a length of input section greater than that corresponding to $CN = 0.3$ would result in little or no added gain if the attenuation of the electromagnetic wave by the attenuation medium is high enough to remove most of the electromagnetic energy. The length of the output section may be adjusted within reason to provide the desired gain for the wave coupled from the output of the propagating structure.

In certain instances and applications a separate external source of potential and the electrodes within the discharge device 15 may be omitted. In these instances, the gas within discharge device 15 would be ionized by providing sufficient power in the radio frequency fields of the waves propagated on the helix, such as occurs in TR devices. This effect can be greatly enhanced by utilizing the longitudinal magnetic field generated by magnet 5 if the magnetic field is the gyroresonant field for the electrons of the gas at the microwave frequency of the waves on the helix. The influence of gas plasma on microwave energy and the gyroresonant effect therein is described in greater detail in the copending application of L. Goldstein et al., Serial No. 232,148, filed June 18, 1951.

Referring to Figs. 4 and 5, an alternative embodiment is illustrated including a cold cathode to establish the gas plasma for attenuation purposes. Device 15 includes an annular-like envelope including a metallic base material 23 inserted in a glass envelope 24 and secured thereto by means of a glass-to-metal seal at 25. The cold cathode material 26 is disposed on the inner surface of base metal 23 and has applied thereto a pulsed potential from source 27. In this embodiment, the helix 4 functions essentially as a ground plane whereby electrons emitted from material 26 will be accelerated back to material 26 for bombardment thereof to produce secondary emission for ionization of the gas within device 15. The cross section of device 15 is an annular-like triangular configuration, the inner dimension of the gas device envelope being substantially tangential to the turns of helix 4 to dispose the gas plasma in a stronger field region of the field adjacent the helical propagating structure.

To dispose the device 15 in a stronger field region of the electromagnetic field adjacent helix 4, a structure as shown in Fig. 6 may be provided. Device 15 having an annular glass envelope 16 has its inner wall 23 configured in a manner to provide a spiral flute 29 to receive the turns of the helix therein and thereby position the gas plasma in a stronger field region of the field about helix 4. It is contemplated that the fluting of envelope 16 would engage the first turns of a helix and when revolved about the axis thereof would thread itself onto the helix for appropriate positioning therealong. The tapered ends of envelope 16 may be sweated to a glass tubing 17a in a manner to provide a continuous rectilinear support for helix 4.

As is known, the maximum electromagnetic field on a helical structure occurs between the turns of the helix. Therefore, if a gas tube or gas plasma could be positioned between adjacent turns of helix 4, the maximum absorption by the gas plasma would be achieved. Fig. 7 illus-

trates an embodiment in which the gas plasma is positioned to be intermediate adjacent turns. This is accomplished by employing a capillary glass tube 30 which is interwoven with a metallic helix 4 and containing therein a suitable noble gas which may be ionized by the radio frequency energy on the propagating structure alone or in combination with the longitudinal magnetic field, the intensity of which corresponds to the gyroresonant frequency of the electrons of the gas plasma. This structure could, of course, have electrodes so disposed as to ionize the gas within capillary tube 30. The entire structure including the helix 4 and capillary tube 30 would be supported for axial alignment with the electron beam by means of non-conducting rods or tubing 17b.

Referring to Figs. 8 and 9, other embodiments of my gas discharge attenuator are shown for use with a traveling wave electron discharge device of the hollow electron beam type wherein the gas discharge device 31 is disposed axially within the helix 4. The principle of absorption by a gas plasma is the same in these embodiments as it is in the previous embodiments. Fig. 8 illustrates that the helix 4 is supported on rods 32 concentric with the hollow electron beam. Gas tube 31 is inserted internally of the rods 32 and as close to the maximum field region of the helical structure as is practical. It is contemplated that the gas tube be concentrated in a relatively short portion of the helical propagating structure but not necessarily limited to such a concentration.

Fig. 9 illustrates diagrammatically the inclusion of a gas attenuator 31 which is coextensive with the helical propagating structure, the outer surface of which is employed to support the helix 4 concentric with the hollow electron beam.

Fig. 10 illustrates the combination of a gas discharge device 33 similar to the discharge device 15 illustrated in Fig. 4 and a traveling wave electron discharge device including a vacuum envelope 34 having a relatively small diameter enclosure utilized as the support for helix 4, as well as the vacuum enclosure. The discharge device 33, for attenuating the waves propagated on helix 4, is disposed about the vacuum envelope 34 and incorporated as an integral part of the metal packaging shell 35 employed to protect the envelope 34 against breakage and shock hazards. Thus, a means has been discovered which will enable the insertion of a deliberate loss on the propagating structure which is effective when disposed externally to the vacuum envelope of the traveling wave tube provided the discharge plasma is in juxtaposition to the electromagnetic field about the helix. With this arrangement, it would be possible to easily replace the loss material or make adjustments thereon without opening the vacuum envelope of the traveling wave tube itself.

The average radio frequency power that can be absorbed by the gas discharge attenuator of this invention is generally limited by the material of the closure or envelope, the electron density of the discharge plasma, the collision frequency of the electrons in the gas and the proximity of the gas plasma to the radio frequency fields surrounding the propagating structure. Absorption of average radio frequency powers in the order of several 100 watts would not be unreasonable. This method of producing the necessary cold loss of a helix or other slow wave structure is more adaptable than present techniques to high power pulse tubes where the peak pulse powers may be large. In addition, the gas tube attenuator can be air or liquid cooled to increase the power absorption limit of the device.

A successful reduction to practice employing the principles of this invention utilized a pulsed discharge in xenon gas at several mm. Hg pressure and produced 10 to 15 db loss at approximately 2600 megacycles. The experimental condition under which the reduction to practice was performed was not optimum since the discharge plasma was not very near the helix nor was the discharge located in a large portion of the radio frequency fields surrounding the helix. Experimentation with cer-

tain of the other noble gas indicated that absorption took place, but was not as high as compared to the loss achieved by employing xenon. It was further shown, however, that the absorption increases if the discharge exists over a longer length of helix and if it occurs nearer the helix. Standing wave measurements at the input to the helix proved the insertion loss provided by the gas discharge was due to absorption rather than reflection of the microwave energy by the plasma.

While I have described above the principles of my invention in connection with specific apparatus, it is to be clearly understood that this description is made only by way of example and not as a limitation to the scope of my invention as set forth in the objects thereof and in the accompanying claims.

I claim:

1. In a traveling wave electron discharge device having a slow wave propagating structure for transmission of radio frequency energy therealong and means to project a beam of electrons parallel to the axis of said propagating structure for interaction with the electromagnetic field of the radio frequency energy transmitted by said propagating structure; an attenuator disposed adjacent said propagating structure for absorption of radio frequency energy propagated therealong, said attenuator comprising a gaseous discharge device disclosed in juxtaposition to the electromagnetic field of said propagating structure whereby ionization of the gas of said gaseous discharge device attenuates the energy propagated along said propagating structure.

2. A device according to claim 1, wherein the gas of said gaseous discharge device is selected from the group comprising helium, neon, argon, krypton and xenon.

3. A device according to claim 1, wherein the gas of said gaseous discharge device is xenon confined at several mm. Hg pressure.

4. A device according to claim 1, wherein said propagating structure includes a helical transmission line and said gaseous discharge device includes a capillary tube interwoven with said helical transmission line for disposition between adjacent turns thereof thereby placing the ionized gas of said gaseous discharge device in the maximum field region of the electromagnetic field of said helical transmission line.

5. A device according to claim 1, wherein said gaseous discharge device is disposed longitudinally of said propagating structure and the outer surface of said gaseous discharge device is tapered radially with respect to said propagating structure at the extremities thereof.

6. A device according to claim 1, wherein said propagating structure has a substantially annular cross-section and said gaseous discharge device is disposed within said propagating structure.

7. A device according to claim 6, wherein said gaseous discharge device is cylindrical, the outer surface of which cooperates in supporting said propagating structure.

8. A device according to claim 1, wherein said gaseous discharge device includes an envelope of annular-like cross-section disposed concentrically about said propagating structure.

9. A device according to claim 8, wherein the annular-like cross-section of said envelope is substantially circular.

10. A device according to claim 8, wherein the annular-like cross-section of said envelope is substantially triangular for disposition of the ionized gas of said gaseous discharge device in closer proximity to the maximum field region of the electromagnetic field of said propagating structure.

11. A device according to claim 8, wherein said propagating structure includes a helical transmission line and the inner surface of said envelope includes a spiral groove thereon for engagement with the turns of said helical transmission line to dispose the ionized gas of said gaseous discharge device in closer proximity to the maximum

field region of the electromagnetic field of said helical transmission line.

12. In a traveling wave electron discharge device having a slow wave propagating structure for transmission of radio frequency energy therealong, means to project a beam of electrons parallel to the axis of said propagating structure for interaction with the electromagnetic field of the radio frequency energy transmitted by said propagating structure, and a magnet concentric to and substantially coextensive with said propagating structure to provide a longitudinal magnetic field to maintain the electrons of said beam parallel to the axis of said propagating structure for substantially the entire length thereof; an attenuator disposed adjacent said propagating structure for absorption of radio frequency energy propagated therealong, said attenuator comprising a gaseous discharge device disposed in juxtaposition to the electromagnetic field of said propagating structure and means including the intensity of the magnetic field of said magnet to ionize the gas of said gaseous discharge device for maximum attenuation of the energy propagated along said propagating structure.

13. In a traveling wave electron discharge device having a conductor in the form of a helix for propagation of radio frequency energy therealong, dielectric material disposed about and substantially coextensive with said helix to provide a rectilinear propagating structure, means to project a beam of electrons axially of said helix for interaction with the electromagnetic field of the radio frequency energy propagated along said helix; an attenuator disposed adjacent said helix for absorption of radio frequency energy propagated therealong, said attenuator comprising an annular glass envelope disposed to surround said dielectric material and in a coupling relation with the electromagnetic field of said helix for a given axial length thereof, the extremities of said envelope being tapered radially with respect to said helix, a high electron density gas enclosed within said envelope, electrodes disposed within said envelope and a source of potential coupled to said electrodes to establish a difference of potential therebetween to ionize said gas for attenuation of the energy propagated along said helix.

14. In a traveling wave electron discharge device having a conductor in the form of a helix for propagation of radio frequency energy therealong dielectric material disposed about and substantially coextensive with said helix to provide a rectilinear propagating structure, means to project a beam of electrons axially of said helix for interaction with the electromagnetic field of the radio frequency energy propagated along said helix; an attenuator disposed adjacent said helix for absorption of radio frequency energy propagated therealong, said attenuator comprising an envelope of annular-like cross-section disposed to surround said dielectric material and in a coupling relation with the electromagnetic field of said helix for a given axial length thereof, a high electron density gas enclosed within said envelope, said envelope including in the outer wall thereof a central portion disposed between two glass end portions, said central portion including a metallic base material coated with a suitable cold-cathode material sealed to each of said end portions, said end portions being tapered radially with respect to said helix, and a source of pulsed potential coupled to said cold-cathode material which in cooperation with the direct current potential of said helix ionizes said gas by secondary electron emission for attenuation of the energy propagated along said helix.

15. In a traveling wave electron discharge device having a conductor in the form of a helix for propagation of radio frequency energy therealong, input means to couple radio frequency energy to the input of said helix, output means to couple radio frequency energy from the output of said helix, dielectric material disposed about said helix extending from the input end and the output end of

said helix to a given central portion of said helix to cooperate in providing a rectilinear propagating structure, a magnet concentric to and substantially coextensive with said propagating structure to provide a longitudinal magnetic field to maintain the electrons of said beam parallel to the axis of said propagating structure for substantially the entire length thereof, means to project a beam of electrons axially of said helix for interaction with the electromagnetic field of the radio frequency energy propagated along said helix; an attenuator disposed in said given central portion for absorption of radio frequency energy propagated therealong, said attenuator comprising an annular glass envelope disposed to be coextensive with said given central portion and in a coupling relation with the electromagnetic field of said helix, said envelope having the ends thereof tapered radially with respect to said helix and the inner surface thereof grooved in the form of a spiral to engage the turns of said helix for cooperation with said dielectric material to provide a rectilinear structure and increase the coupling to said electromagnetic field and a high electron density gas enclosed within said envelope whereby the energy of the radio frequency wave and the longitudinal magnetic field of said magnet cooperate to ionize said gas for attenuation of the energy propagated along said helix.

16. In a traveling wave electron discharge device having a metallic helix for propagation of radio frequency energy therealong, dielectric material disposed about and substantially coextensive with said metallic helix to provide a rectilinear propagating structure, means to project a beam of electrons axially of said metallic helix for interaction with the electromagnetic field of the radio frequency energy propagated along said metallic helix; an attenuator disposed adjacent said metallic helix for absorption of radio frequency energy propagated therealong, said attenuator comprising a capillary tube in the form of a glass helix disposed to be intermediate the turns of said metallic helix having the same helical diameter as said metallic helix, and a high electron density gas enclosed in said tube whereby the ionization of said gas provides

maximum attenuation of the energy propagated on said metallic helix.

17. In a traveling wave electron discharge device having a conductor in the form of a helix for propagation of radio frequency energy therealong, dielectric material disposed within and substantially coextensive with said helix to provide a rectilinear propagating structure, means to project a hollow beam of electrons parallel to the axis of said helix for interaction with the electromagnetic field of the radio frequency energy propagated along said helix, said helix being disposed within said beam of electrons; an attenuator disposed adjacent said helix for absorption of radio frequency energy propagated therealong, said attenuator comprising a cylindrical envelope disposed within said dielectric material to be in a coupling relation with the electromagnetic field of said helix for a given axial length thereof, the extremities of said envelope being tapered radially with respect to said helix, and a high electron density gas enclosed within said tube whereby the ionization of said gas provides attenuation of the energy propagated along said helix.

18. In a traveling wave electron discharge device having a conductor in the form of a helix for propagation of radio frequency energy therealong, means to project a hollow beam of electrons parallel to the axis of said helix for interaction with the electromagnetic field of the radio frequency energy propagated along said helix, said helix being disposed within said beam of electrons; an attenuator disposed adjacent said helix for absorption of radio frequency energy propagated therealong, said attenuator comprising a cylindrical envelope disposed within said dielectric material and in a coupling relation with the electromagnetic field of said helix for a given axial length thereof, the extremities of said envelope being tapered radially with respect to said helix, and a high electron density gas enclosed in said tube whereby the ionization of said gas provides attenuation of the energy propagated along said helix, said envelope cooperating to support said helix over said given axial length.
